ALBERT OTTO AND WILLIAM OTTO, OF KANSAS CITY, MISSOURI, ASSIGNEES OF ONE-HALF TO FRANCIS E. SCOTT AND GLENN BUTLER, BOTH OF KANSAS CITY, MISSOURI.

COMPRESSED-AIR AUTOMATIC OIL AND WATER PUMP.

1,358,238.

Specification of Letters Patent. Patented Nov. 9, 1920.

Application filed June 2, 1919. Serial No. 301,139.

To all whom it may concern:

Be it known that we, ALBERT OTTO and WILLIAM OTTO, citizens of the United States of America, residing at Kansas City, in the county of Jackson and State of Missouri, have invented certain new and useful Improvements in Compressed-Air Automatic Oil and Water Pumps; and we do hereby declare that the following is a full, clear, and exact description of the invention, reference being had to the accompanying drawings, forming a part of this specification.

The invention has for its objects,

First. A pump for oil and water which is self-operative to effect a displacement of the oil and water by the expansive force of compressed air or elastic fluid.

Second. An automatic pump operative by the expansion of the compressed air or elastic fluid at high or low pressure.

Third. An automatic pump for oil wells which will keep the sand in the well, be constantly covered with the oil, and may be regulated in its pumping action to the height of the oil within the pump.

Fourth. In a compressed air pump, to effect the pump action automatically at the various water levels within the pump and continuous action at shallow depths.

Fifth. In a compressed air or gas pump to control by the expansion of the air or elastic fluid, the air pressure upon the oil or water within the pump.

Sixth. To eliminate the sand action upon the pump in oil wells.

The invention consists in the novel construction and combination of parts such as will be first fully described and then specifically pointed out in the claims.

In the drawings,

Figure 1, is a vertical sectional view of an oil well and the casing, showing the novel pump within the oil sand, also showing the air compressor at the surface of the ground and compressed air tank, and oil tank, a three-way pipe joint coupling connecting said tanks, a compressed air pipe leading therefrom to the pump, and the oil pipe extending through said pipe to the oil tank; also showing the inlet pipe for the compressed air to the pump and the tube for the compression spring.

Figs. 2 and 2^a, are vertical sectional views

enlarged of the novel pump in two halves, showing the high pressure inlet valve pipe for the compressed air and the automatic air controlling devices, to the compressed air, the float being positioned at an intermediate point within the pump cylinder.

Fig. 3, is a detail vertical sectional view of the upper portion or head of the pump cylinder, taken on line 3—3 on Fig. 7, showing the conduit for the oil from the cylinder and the compressed air pipe, the compressed air tube on the cylinder head, and compression spring and plunger, the tripping wheel and dogs, the rack on the plunger held by the tripping wheel, and the lever controlling the air inlet valve actuated by the rack.

Fig. 4, is a side view of the upper end or head of the pump cylinder, as seen in Fig. 1, taken from a position to left of the pump, showing the high pressure valve pipe and the exhaust pipe, also showing the tube on the pump head carrying the spring and plunger and the pipe connection therefrom for the excess of compressed air in the tube connected with the exhaust valve pipe.

Fig. 5, is a detail vertical sectional view of a portion of the cylinder head or cap plate and the portions of the inlet and exhaust pipes within the cylinder and the spring controlled valve stems, and valves for the compressed air, taken on the line 5—5 on Fig. 8.

Fig. 6, is a detail view in perspective of the supporting block or hanger for the tripping cog wheel secured to the cylinder head showing the dogs and connecting spring the slideable bracket and inclined planes on the bracket and the rollers on the dogs upon the inclined planes, also showing a portion of one of the lever arms pivoted to and operating the slideable bracket.

Fig. 7, is a transverse sectional view taken on line 7—7 on Fig. 2, showing the well casing, the compressed air pipe and oil pipe in horizontal section and the upper portion of the air inlet valved pipe, also showing the cylinder head or cap to the pump cylinder and the exhaust pipe, and the tube carrying the compression spring.

Fig. 8, is a transverse sectional view taken through the well casing pump cylinder and air inlet and exhaust pipes, on line 8—8 on Fig. 2, looking upwardly.

Fig. 9, is a transverse sectional view taken through the pump cylinder and the hollow cylindrical float on line 9—9 on Fig. 2^a.

Fig. 10, is a transverse sectional view taken through the pump cylinder and the oil tube on line 10—10, on Fig. 2^a.

Fig. 11, is a vertical sectional view of the lower end of the oil tube and valve casing, showing the ball valve.

10 Fig. 12, is a transverse sectional view of the pump cylinder taken on the line 12—12 on Fig. 2^a, showing the flap valve admitting the oil and water to the pump cylinder.

15 Similar numerals of reference indicate corresponding parts in all the figures of the drawings.

Referring to the drawings,

15 indicates the cylinder of the pump, which for the one purpose illustrated in its 20 application to oil wells, is made of considerable length, and of the circumference requisite to be introduced within the casing to said wells.

25 The upper end of the pump cylinder is internally screw-threaded at 16 and a cylinder head or cap 17 of the same circumference as the cylinder closes hermetically by the gasket 17' the end of the cylinder, this cap or head being provided with a 30 downwardly extended externally screw-threaded flange 18 which is fitted to the screw-threaded portion 16 of said cylinder.

The lower end portion of the cylinder 15, is also internally screw-threaded at 19, and 35 within this screw-threaded opening is fitted an externally screw-threaded plug 20, having a central opening 21. A flap valve 22 extends over said opening, its lip 23 being secured to the plug by the screws 24. 40 This valve is provided with a circular weighted disk 25, secured to the valve by the screw 26.

27 indicates the discharge pipe for the oil within the pump cylinder 15, the lower 45 end of which pipe extends downwardly to a position a short distance above the flap valve 22 and is externally screw-threaded at 28, see Fig. 11.

29 indicates a valve casing having upper 50 and lower end members 30 and 31 respectively, the upper end member having a screw-threaded opening 32, in which is fitted the externally screw-threaded lower end of the pipe 27. The lower end 31 of the valve casing is provided with an inlet opening 32', having a valve seat 33 in which is seated a ball valve 34. The lower end 31 of the casing has a short flange 32' extending around the opening 32.

60 The lower end of pipe 27 within the casing 29 is notched at 35 upwardly to permit the oil to escape up the pipe past the ball valve.

The upper end of the pipe 27 is externally screw-threaded at 27' and extends

within the screw-threaded opening 36, in the center of the head or cap 17 to the pump cylinder, and a short distance above said head and within a screw-threaded upward extension 37 of said cap plate, extending 70 around said opening and within which opening is inserted the lower end of a short pipe 38.

The upper end of pipe 38 is externally screw-threaded at 39 and above said pipe 75 is a pipe 40 of the same circumference and externally screw-threaded at 41, the adjacent ends of pipes 40 and 38 being connected by an internally screw-threaded pipe coupling 42.

On the screw-threaded portion of the pipe 40, above the pipe coupling, is a gasket 43.

44 indicates a pipe coupling of a larger circumference than pipe coupling 42, and 85 having a screw-threaded opening in its lower half and fitted to the screw-threaded portion of pipe 40 and turned down on the gasket or washer 43. The upper half of the coupling is made with an opening considerably larger in circumference than the pipe 40 and screw-threaded at 45, the screw threads terminating at the shoulder 45' which closes the opening, the pipes 38 and 40 being a continuation upwardly of 90 the oil pipe 27.

46 indicates the compressed air pipe larger in circumference than pipe 40, its lower end being externally screw-threaded and fitted within the screw-threaded upper half 100 of the pipe coupling 44, the upper end of the said pipe extending upwardly to the surface of the ground, as further described. With the side of the air pipe 46, immediately above the coupling 44, is connected 105 the upper curved end of the air inlet pipe 47, the lower end of which pipe extends downwardly part way within a screw-threaded opening 48 in the head or cap 17 to the pump cylinder, at a point immediately forward of a line extending diametrically to the oil tube 27, as seen in Figs. 5 and 7.

Surrounding the oil pipe 27, within the pump cylinder, is a vertically slidable thin 115 pipe 50, see Fig. 3, approximately as shown half the length of the oil pipe 27 and slightly larger in circumference than said pipe. Upon the upper end of the pipe is rigidly connected a flange or collar 51, and upon the lower end of said pipe is an adjustable collar 52 having an adjusting screw 52'.

Upon the oil pipe 27, beneath the lower end of pipe 50, is mounted a collar 53 and fixedly secured thereto.

Upon pipe 50, is slidably mounted a hollow cylindrical air tight drum 55, which performs the office of a float, see Fig. 9. Through the center of the float extends a tube 56, hermetically sealed within the open- 130

ings to said drum, its upper end extending upwardly at 56° a short distance above the upper end of said drum and its lower end a short distance below the lower end of said drum at 56° , see Figs. 2-2a. A valve 55' on the drum admits air to the drum to equalize the pressure on the outside. Upon the lower end of the oil pipe 27, immediately above the casing 29, for the ball valve, is a circular spoked wheel 57 slightly smaller in circumference than the inner circumference of the pump cylinder and having a hub 58 mounted on the oil pipe 27, see Fig. 10.

The hub 58 is provided with a set screw 59 securing the wheel to the oil pipe. The wheel serves to keep the oil pipe from lateral movement in the pump cylinder, the oil passing upwardly through the openings 58° between the spokes, see Fig. 10.

Within the pump cylinder and supported by the head or cap 17, are the separate tubular inlet valve casing 60, and the tubular exhaust valve casing 61, arranged a short distance apart, see Fig. 5. The upper end 20 of valve casing 60 is externally screw-threaded and is fitted within the lower screw-threaded portion of the opening 48 receiving the lower end of the air inlet pipe 47, the opening 60' in the upper end of the 25 valve casing 60 being of the same size as the opening in the inlet pipe 47, both being in communication. The valve opening 60' extends downwardly a short distance to a valve seat 60° and beneath said valve seat 30 the opening 60' in the valve casing 60 is reduced slightly in circumference.

62 indicates the valve stem within the casing 60, a portion concentric with the upper end of said stem being cut away below the 40 head of the stem and inclined inwardly at 61° beneath said head to enter the valve seat 60° in the valve casing 60. Beneath the valve seat 60° a short distance in the valve casing, is a transverse inlet opening 63 for the compressed air to the pump cylinder.

The lower end of the valve stem 62 extends a short distance below the line of the lower end of the valve casing 60 and upon said end is loosely mounted a perforated block 50 64, and upon said stem, above the block, is a fixed collar 65. On the lower end of the 55 stem is a fixed collar 66, and extending around said stem is a spiral spring 67, one end bearing on said collar 66, and the other end on the lower end of block 64.

In the cap plate or head 17 of the pump cylinder immediately in rear of the opening 48, in said plate, for the compressed air pipe 47, (see Fig. 7), is a screw-threaded opening 67, in which is fitted the screw-threaded upper end of the aforesaid exhaust valve casing 61, the said end terminating a short distance above the cap plate 17 of the pump cylinder. The longitudinal opening 69 in 60 the upper end of the valve casing 61, is re-

duced in circumference a short distance below the upper end of the casing to form a neck 70, and on the lower portion of said neck a valve seat 71. 72 indicates the valve stem within the valve casing which is provided with a beveled head 73 adapted to fit the valve seat 71.

In the valve casing, a short distance below the valve seat, is a transverse opening or port 74, which is closed by the valve stem 75 72, following the admission of compressed air to the pump cylinder through the inlet opening 63.

The lower end of the valve stem 72 extends a short distance below the lower end of the 80 valve casing 61, and upon said end is loosely mounted a block 75 having an opening for the stem therethrough, and on said stem above the block is a spiral spring 76, one end bearing on the upper end of said block, and the other end on a collar 76' fixed to said stem a short distance upwardly. On the lower end of said valve stem, is fixed a 85 collar 77, retaining said block on the stem.

A connecting pin 78, screw-threaded at 90 both ends, extends at one end within a screw-threaded opening in the block 64, and at the other end within a screw-threaded opening in block 75. 79 indicates a supporting rod or bar fixedly connected at its upper 95 end to the inner surface of the cap plate or head 17 of the pump cylinder, the lower end of said bar extending downwardly to a position immediately in rear of the pin 78.

80 indicates a lever consisting of a horizontal flat bar, the short end being forked, to receive the pin 78, the lever or bar being pivoted at 80° to the said lower end of the bar 79. The long arm of said lever is bent in a curved line and extended forwardly a 100 short distance around the oil tube 27, and thence a short distance past said tube and at a tangent thereto, see Fig. 8.

In the cylinder head or cap plate 17, a short distance forward and to the right of the opening 36 for the oil pipe 27, is a screw-threaded opening 81. See Figs. 3 and 7.

82 indicates a block or bracket within the pump cylinder nearly rectangular in form and having an externally screw-threaded 115 nipple 83 rigidly connected with the upper end of said bracket adjacent its outer surface toward the pump cylinder. This nipple is fitted to said screw-threaded opening 81 in the cap plate 17, and extends part way 120 therein. Extending downwardly from the nipple through the bracket is a vertical opening 84. Extending inwardly from the lower portion of the bracket from the vertical opening 84, and through the inner longitudinal surface of said bracket, is a narrow recess 85.

86 indicates an arm pivoted at its lower end to the collar 51, on the upper end of the sliding pipe 50, see Fig. 2. With the upper 130

end of the arm 86, is pivotally connected at 87* one end of an arm 87, the other end of which arm extends upwardly at an angle to the arm 86 to a position upon the forward 5 side of the bracket 82, a short distance upwardly from the lower end of said bracket.

Through the latter end of arm 87 extends a pivot bolt 88, having a tap to hold the arm 87 loosely against the bracket, which also 10 extends through the bracket and recess 85. Within this recess 85 and mounted on the pivot bolt 88, is a cog wheel 89.

90 indicates the upper dog which is pivoted at its inner end at 90* to the bracket 15 82 in the upper portion of recess 85 and extends outwardly and downwardly and engages between the cogs of wheel 89.

91 is the lower dog which is pivoted in the lower portion of the recess 85, on the pivot 20 91* extending through said bracket, the dog extending upwardly and engaging at the proper time between the cogs of wheel 89.

Each of the dogs 90 and 91 is constructed with a lateral projection on its free end, the 25 face of which remote from the pivot of the dog is in a plane at right angles to the longitudinal axis of the dog, while the face toward the pivot is inclined to said axis, so that the dog constitutes a pawl, preventing 30 rotation of the cog wheel toward the pivot but permitting its rotation from the pivot.

Through the forward ends of dogs 90 and 91, extend transversely the pins or pivots 92 and 93 respectively. With these pivots 35 on the rear sides of the dogs 90 and 91, are connected the respective ends of a light spiral spring 94, (see Fig. 6), so as to keep the dogs 90 and 91 engaged alternately with the wheel 89.

40 95 indicates a vertically movable dog releasing block, located between the wheel 89 and the forward side of the bracket, and setting out from the bracket as it moves upwardly, and acting as a stop in the fall of the arm 87. The outer vertical portion of the block 95 is notched from its upper end downwardly and thence inclined outwardly and downwardly, to form a bearing surface 96, and the lower end of said block is 45 notched in a similar manner, and the bearing surface 97 inclined outwardly and upwardly. On the pin 92 on the dog 90, which extends from said dog toward the sliding block 95, is a roller 98, which bears on the 50 inclined surface 96 of said block, and on the pin 93 on the dog 91 is a roller 99 which bears on the inclined surface 97 of the block 95. In the arm 87, which extends past the block 95, is an opening 100, and in the block 55 95 is a pin 101 extending outwardly through said opening 100. The automatic valve operating device consists of a tube 102 having an external screw-thread at its lower end which is fitted to the upper half of the 60 screw-threaded opening 81 in the cap plate 65

or head 17 of the pump cylinder. This tube extends a considerable distance upwardly from the upper surface of said plate 17 and its upper end is internally screw-threaded. In said end, is fitted a screw-threaded plug 70 103, secured from movement by a screw 104. A small air tube 105 is secured to the outer portion of the plug the opening in which is extended through the plug, to admit the air as the plunger 107 moves downward and prevent a vacuum in the tube. Within the tube is an expanding coiled spring 106, its upper end bearing on the inner side of plug 103, and its lower end extending downwardly a distance approximately one-half the distance 75 from the upper to the lower end of said tube and bears against the slidable plunger 107, in which is a screw-threaded opening 108, in which opening is fitted the upper screw-threaded end of a rod 109.

110 and 111 are cup-shaped leather washers on the rod 109, immediately below the plunger 107, and which bear frictionally on the inner surface of the tube 102.

The lower end of the rod 109 extends 90 downwardly through the opening 84 in the bracket 82 and to a position a short distance below the lower end of bracket 82 and loosely within said opening in the bracket and is notched at intervals to form a rack 112 95 which rack moves in engagement with the cog teeth of the wheel 89. The air is thus permitted to pass the rack and enter the tube 102 and actuate the plunger.

The extreme lower end of the rack 112 100 is screw-threaded and upon said end is fitted a screw-threaded collar 113, and beneath said collar is a lock nut 114 having a screw-threaded opening fitted to said end of the rack, which nut is in contact with the forward side and outer end of the lever 80 operating the valve stems 62 and 72. Through said nut 114 and the screw-threaded end of the rack 112, extends a pivot 115, which pivot extends through the outer end 110 of the lever 80.

116 represents an oil well and 116' the casing, which extends downwardly to the ordinary depth or to the oil sand. At the surface of the ground, 117 indicates an air compressor and 118 a storage tank for compressed air, from which leads a pipe 119 to a three-way pipe joint 120. 121 indicates a storage tank for the oil, and 122 a pipe leading from the three-way joint to the oil 120 tank.

The upper end of the compressed air pipe leading from the pump is connected with the three-way pipe joint 120, and the oil pipe 27 extends upwardly within pipe 46, 125 and the pipe joint 120, and is connected with the pipe 122 leading to the oil tank. A valve 119* is shown in pipe 119. The pump cylinder 15, with its air conducting pipe 46, is lowered to the bottom of the well and 130

within the oil sand which has been removed in the drilling operations. In operation the oil entering the opening 21 in the plug 20 at the lower end of the pump cylinder raises 5 the flap valve 22 and rises in said cylinder. When the inlet and exhaust valve stems 62 and 72, and the respective valve heads in the respective valve casing 60 and 61, are in the position seen in Fig. 5, the inlet valve 10 head of the stem 62 is on the valve seat 60* and closed, while the valve stem 72 is in an open position as respects the exhaust openings 70 and 74 and held down by the lever 80, the cog wheel 89 being locked 15 against rotation under the influence of spring 106 by the engagement of the abrupt face of the upper dog with the cogs on the cog wheel. Compressed air from the storage tank 118 is then admitted to the pipe 46, 20 which passes into the inlet pipe 47 to the valve head on the valve stem 62.

The float or drum 55 in the pump cylinder is shown at an intermediate position on the slidable pipe 50. As the oil rises in the 25 pump cylinder 15, its pressure forces upwardly said float or drum 55 from its position on the said pipe 50 until said float comes into contact with the collar 51 on the upper end of said pipe and raises the pipe and, 30 through the pivoted bars 86 and 87 raises the block 95, which moves a slight distance outwardly from the bracket 82, and the upper inclined bearing surface on said block acts on the roller 96 to raise the dog 90 from 35 between the cogs on the cog wheel 89. At the same time, the lower dog is disengaged from the block 95 and is brought by the spring 94 into engagement with the cog wheel 89, its abrupt face preventing the rotation of the cog wheel anti-clockwise. The 40 spring 106 then depresses piston 107 and rack 112, which rotates cog wheel 89 clockwise, the lower dog slipping over the cogs on said wheel, permitting the rack to move 45 the long arm of lever 80 downward, thereby opening the inlet valve on stem 62 and closing the exhaust ports 70 and 74. Thus compressed air is admitted to the cylinder 15, driving oil therefrom through pipe 27, 50 and the tendency of the pressure on the lower side of piston 107 to shift the valves to their former positions cannot become effective until the lower dog is disengaged from the cog wheel.

55 While the compressed air is exerting its pressure within the pump cylinder upon the oil, it also enters the opening 84 in the bracket 82 for the rack 112, and enters the tube 102 in the cylinder head 17, exerting a 60 pressure on the cup-shaped washers 110—111 in said tube. When the lower dog is disengaged from the cog wheel, the compressed air forces the plunger 107 upwardly within the tube, thereby compressing the spring 106, and also drawing upwardly the rack 65

bar 112 in the opening 84 in the bracket, and drawing up the long arm of the lever 80 pivoted to said bar, thereby closing the inlet valve on steam 62 on its seat and opening the exhaust ports 70 and 74, relieving the 70 pressure of the air on the oil in the pump cylinder.

When the float has moved downwardly to the adjustable collar 52 on the tube 50, the tube 50 is drawn downwardly, which 75 draws down on the arms 86 and 87, and the lower inclined bearing 97 on the slidable block moves the lower dog 91 out of engagement with the cog wheel 89 and the compressed air within the cylinder and tube 80 forces the rack 112 upwardly, compressing the spring 106 in the tube 102, and the upper dog 90 falls down with the spring tension between the cogs of wheel 89, holding said wheel as an escapement from rotation clockwise 85 until the float rises again in the pump cylinder and releases the dog, when the operation of the devices as described, is repeated.

By making the tube 50 of increased length, 90 the float 55 will move farther in its downward movement, thereby pumping a larger quantity of oil from the pump cylinder, or by adjusting the collar 52 upwardly on pipe 50 the movement of the float may be lessened 95 and the quantity of water or oil supply thus regulated. In our invention the float is not held down by extraneous means or submerged in the incoming liquid, but is free to rise and fall at the various fluid levels, hence 100 nonsubmerged and its action effective at high and low levels in its reciprocal movements.

The pump is adapted to be used for pumping water from cisterns or ordinary wells, and distributed from a storage tank similar 105 to the tank 118 under pressure or pumped directly to the consumer without using the storage tank.

Such modifications of the invention may be employed as are within the scope of the 110 appended claims.

Having fully described our invention, what we now claim as new and desire to obtain by Letters Patent is,

1. In a compressed air pump, the combination with the pump cylinder having a head, an internal liquid eduction pipe, air inlet and exhaust valves controlling alternately the inlet and exhaust of the compressed air, a source of supply of compressed air leading to the cylinder, an automatic device controlled by the pressure of compressed air actuating the opening and closing of the valves, and locking means governing the action of said device, an independently movable float, and devices actuated reciprocally by the float in the rise and fall of the liquid within the cylinder governing the action of the said locking means. 115
2. In a compressed air pump, the combi- 120
3. In a compressed air pump, the combi- 125
4. In a compressed air pump, the combi- 130

- nation with the cylinder having a head, of an internal liquid discharge pipe extending through said head, a source of compressed air leading within the cylinder, compressed air inlet and exhaust valves to said cylinder, valve operating devices acting intermittently and alternately to admit the compressed air and exhaust the same from the cylinder, an air compression tube, a plunger and a spring actuated by the pressure of the compressed air in the pump cylinder, a combined plunger rod and rack actuating the valve operating devices, a cog wheel and an escapement controlling the rack, and means controlled by the level of the liquid within the pump cylinder for controlling the escapement.
3. In a compressed air pump, the combination with the pump cylinder and its head, and with an internal liquid discharge pipe extending through said head, of a source of compressed air leading within the cylinder, means for admitting and controlling the inlet and exhaust of the compressed air in the pump cylinder, a slidable pipe concentric with the liquid discharge pipe, and a float on said pipe, and means for regulating the operative position of said float on said slidable pipe.
4. In a compressed air pump, the combination with the pump cylinder and its head, and with an internal liquid discharge pipe extending through said head, a source of compressed air leading within the cylinder, air inlet and exhaust valves for controlling the admission and exhaust of the compressed air within the cylinder, valve operating devices within the cylinder, a slid- 30 able pipe co-axial with said liquid dis- charge pipe, a floating drum on said pipe, and an adjustable collar in the downward path of movement of said drum.
5. In a compressed air pump, the combination with the pump cylinder and its head, and with an internal liquid discharge pipe extending through said head, of a source of compressed air leading to said cylinder, air inlet and exhaust valves for admitting and controlling the entrance and exhaust of the compressed air to the cylinder, and the valve operating devices connected with said valves, a slidable pipe extending around the liquid discharge pipe, a slidable float on said pipe, a source of power and releasable power transmitting devices connected with the valve operating devices and releasing means therefor governed by said float in its rise and fall.
6. In a compressed air pump, the combination with the pump cylinder and its head, and with an internal liquid discharge pipe extending through said head, and with a source of compressed air, and a pipe conducting compressed air to the cylinder, and with inlet and exhaust valves and valve

stems, of a lever actuating the valve stems, a compressed air operated power generating and imparting device connected with said lever, means for holding releasably said power imparting device in a non-operative 70 position, a float in said cylinder, and power-releasing tripping devices actuated by the float, for releasing said power imparting device.

7. In a compressed air pump, the combination with the cylinder and cylinder head, and with compressed air inlet and exhaust valve casings within the cylinder connected with the cylinder head and having suitable valve seats and inlet and exhaust ports, and with the valves and valve stems on said valves, of blocks having openings through which said stems extend, springs on said stems controlling said valves in their valve closing movements 80 and suitable collars on said stems above and below said blocks.

8. In a compressed air pump, the combination with the pump cylinder and its head, and with compressed air inlet and exhaust valve casings connected with the cylinder head, and having suitable valve seats, and inlet and exhaust ports, and with the valves and valve stems on said valves, of blocks having openings through which said stems 95 extend, springs on said stems, controlling their valve closing movements, collars on said valve stems above and below said blocks, a connecting device connecting said blocks on said stems with each other, a pivoted operating lever connected with said device, and means for operating said lever intermittently.

9. In a compressed air pump, the combination with the cylinder and cylinder head, and with a compressed air pipe on said head, and with the air inlet and exhaust valves, and with the valve operating devices, of a compressed air operated mechanism for operating said devices, consisting of a tube connected with said head, an expansion spring in said tube, a plunger and a combined rod and rack connected thereto, a cog wheel and dogs adapted to engage alternately with said wheel, a spring connecting one dog with another, and a tripping device for tripping the dogs alternately.

10. In a compressed air pump, the combination with the cylinder and cylinder head, and with air inlet and exhaust valves, and with a pivoted lever operating said valves, of a tube on the cylinder head extending within said head and having a closed outer end, a bracket on the said head within the 125 pump cylinder having an opening in communication with the opening in said tube, a compression and expanding spring in said tube, a plunger, and a combined plunger rod and rack acting against said spring 130

and connected with the valve operating lever, a cog wheel on the bracket engaging with said rack, dogs on said bracket, adapted to engage alternately with said cog wheel, 5 a slideable dog releasing device on the bracket and means for operating the dog releasing devices.

11. In a compressed air pump, the combination with the cylinder and cylinder head, 10 and with air inlet and exhaust valves, and with a pivoted valve operating lever, of a tube on the cylinder head extending within said head and having a closed outer end, a bracket on the said head within the pump 15 cylinder having an opening in communication with the opening in said tube, a compression and expansion spring within said tube, a plunger and a combined plunger rod and rack acting against said spring and 20 connected with the valve operating pivoted lever, a cog wheel on the bracket engaging with said rack dogs pivoted on said bracket, and adapted to engage alternately with said cog wheel, a coiled spring connecting one 25 dog with the other, rollers pivoted to said dogs, and a vertically movable block on said bracket having oppositely inclined roller bearing surfaces for said rollers, and means for imparting an operative movement to 30 said block.

12. In a compressed air pump, the combination with the pump cylinder and cylinder head, and with an internal liquid discharge pipe extending through said head, and with a source of compressed air and a compressed pipe larger in circumference and co-axial 35 with the liquid discharge pipe extending in the direction of the cylinder head and having a closed lower end, inlet and exhaust 40 tubular valve casings within the cylinder extending through said head, said inlet tubular valve casing extending upwardly and connected with the compressed air pipe, said inlet and exhaust tubular valve casings having 45 valve seats and ports and valve stems and valves on said stems within the valve

casings, a connecting device connecting one valve stem with the other, a pivoted valve operating lever connected with said device, a float within the cylinder and devices actuated by the rise and fall of the liquid, adapted to impart motion to the pivoted 50 valve operating lever.

13. In a compressed air pump, the combination with the cylinder and cylinder head, 55 and with a liquid discharge pipe extending through said head, of a slideable pipe co-axial with the liquid discharge pipe having a collar at its upper end, a floating drum, a tube hermetically connected with the drum, 60 and through which said slideable pipe extends, an adjustable collar on said slideable pipe beneath said drum, a bracket within the cylinder connected with the cylinder head having a recess and a vertical opening 65 extending past said recess, a cog wheel pivoted to said bracket within said recess, a tube on the cylinder head communicating with the cylinder and having a closed outer end, a compression and expansion spring in 70 said tube, a plunger, and a combined plunger rod and rack extending through the opening in said bracket and engaging with the cog wheel, suitable air inlet and exhaust valves to said cylinder and a pivoted lever 75 connected with said combined plunger rod and rack dogs on said bracket and a spring connecting said dogs, a vertically movable block on said bracket having inclined surfaces at each end, rollers on said dogs bearing 80 on said inclined surfaces, and arms pivoted on the collar on the upper end of said slideable pipe on the liquid discharge pipe, one of said arms being pivotally connected 85 with said bracket and also pivotally connected with the sliding block on said bracket.
